UNITED STATES PATENT OFFICE

2,542,118

MILK CAN HOLDER

Willard L. Christman, Tony, Wis.

Application January 20, 1947, Serial No. 723,124

1 Claim. (Cl. 220—15)

1

This invention relates to new and useful improvements in milk can holders and the primary feature of the present invention is to provide a holding device for milk cans adapted to hold same in an upright and steady position in a cooling tank while fresh warm milk is being poured into the can.

Another important feature of this invention is to provide a device of the character referred to that is adapted to hold a milk can in such a manner during a filling process that the can will not tip over or slip sideways thereby spilling milk.

A further feature of the present invention is to provide a device of the class described that is simple and practical in construction, strong and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the milk can holder device constructed in accordance with the present invention.

Figure 2 is a view in elevation thereof, the lower portion of said holder embedded in a concrete floor.

Figure 3 is an enlarged sectional view taken on line 3—3 of Figure 1.

Figure 4 is an elevational view showing the manner in which the holder is adapted to receive a usual milk can.

Figure 5 is a top plan view showing the manner in which the holder is pivoted outwardly to remove the can therefrom.

Figure 6 is a sectional view taken on line 6—6 of Figure 3.

Referring now to the drawings in detail wherein for the purpose of illustration, I have disclosed a preferred embodiment of the present invention, the numeral 5 represents a hollow sleeve having its lower portion embedded in a concrete floor 6 away from a vertical wall 7.

A plate 8 preferably welded as at 9 to the lower end of said sleeve is adapted to prevent any injurious matter from entering said sleeve and to aid in the anchoring of said sleeve.

A vertical fin 10 welded as at 11 to the lower portion of said sleeve is also embedded into said floor 6 and prevents any twisting or turning action of said sleeve.

The lower end 12 of a vertical standard 13 is rotatably carried in sleeve 5 and a rib 14 projecting outwardly from said lower end 12 is adapted to engage a notch 15 provided in the upper edge of sleeve 5 for locking said standard 13 in non-rotatable position.

A substantially semi-cylindrical frame designated generally by the numeral 16 is composed of a pair of vertical arms 17 integrally formed at their upper ends into an upper arcuate cross connecting arm 18 and at their lower ends into

5 21 a lower arcuate cross connecting arm 19, said arms 18 and 19 are to be curved to conform to the periphery of a usual milk can 20 and the centers of said arms are preferably welded as at 21 to the standard 13.

When the frame 16 is locked in position as shown in Figure 1 the vertical arms 17 of said frame extend outwardly from wall 7 in a like manner and the can 20 held by said frame just slightly from said wall 7 so that the can cannot tilt in any direction.

In order to remove the can from the frame, standard 13 is raised slightly until rib 14 disengages notch 15, the standard and frame are 15 then pivotally swung to one side in a manner shown in Figure 5 of the drawings.

It is obvious from the drawings that the device is not designed to hold the can 20 in an elevated position as the bottom of the can rests on the 20 floor 6 but rather the device is adapted to support the can during the filling process.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even 30 though there is herein shown and described a preferred embodiment of the invention the same is susceptible to certain changes fully comprehended by the spirit of the invention as herein described and the scope of the appended claim.

35 I claim:

A device for holding cans against a wall comprising a frame composed of upper and lower horizontal arcuate members, vertical members connecting the ends of the upper and lower members to each other, a vertical standard rigidly secured to the mid-portion of the arcuate members and extending downwardly below the lower arcuate member, a sleeve embedded vertically in a foundation and formed with a notch 45 in its upper end at the side of the sleeve remote from the wall, said sleeve rotatably receiving the lower end of the standard, and a lug on the standard resting on the upper edge of the sleeve and gravitating into the notch to lock the frame 50 in a closed position embracing the can.

WILLARD L. CHRISTMAN.
